UNITED STATES PATENT OFFICE.

REINHARD HILDEBRAND, OF WEBSTER GROVES, MISSOURI, ASSIGNOR TO FULTON IRON WORKS COMPANY, OF ST. LOUIS, MISSOURI, A CORPORATION OF DELAWARE.

VALVE-CONTROLLING DEVICE FOR INTERNAL-COMBUSTION ENGINES.

Application filed June 23, 1919. Serial No. 306,177.

To all whom it may concern:

Be it known that I, REINHARD HILDEBRAND, a citizen of Germany, a resident of Webster Groves, in the county of St. Louis, 5 State of Missouri, have invented certain new and useful Improvements in Valve-Controlling Devices for Internal-Combustion Engines, of which the following is a full, clear, and exact description, reference 10 being had to the accompanying drawings, forming a part of this specification.

My invention relates to improvements in valve controlling devices for internal combustion engines, and more particularly to 15 an adjustable means for operating the inlet valves of such engines. The invention is especially adapted for use in internal combustion engines of the type wherein air is compressed to a temperature high enough 20 to ignite the fuel.

Prior to this invention, engines of this type have been provided with inlet valves, known as injection valves, for the admission of liquid fuel which is injected into the 25 cylinders by means of blasts of compressed air. To obtain the desired ignition temperature, it is necessary to subject the air in the cylinder to a very high compression, for example, about 500 pounds per square 30 inch, and the air blast for injecting the fuel must be under a higher pressure, for example, about 800 pounds per square inch. In considering the present invention, it will be interesting to observe that heat may be 35 generated by the compression of air, and if compressed air is permitted to expand, it will absorb heat from adjacent bodies, thereby cooling the adjacent or surrounding bodies. When the blast of air at a relatively 40 high pressure is injected into the highly heated air in the engine cylinder, the air blast expands and as a result it tends to cool the fuel with which it is commingled. The cooling influence of the expanding air blast will depend upon the difference 45 between the pressure of the injection air and the pressure of the hot air in the cylinder, and also upon the volume of the injection air admitted to the cylinder. Therefore, if too much injection air is admitted 50 into the cylinder, it will impair the efficiency of the engine by unduly cooling both the fuel and the hot air whereby the fuel is to be ignited.

The liquid fuel is usually forced to the

inlet valve in measured charges, which vary in accordance with changes in the speed of the engine, the fuel supply being ordinarily regulated by a fuel pump under the control of a speed governor. In other words, the quantity of fuel is determined by the action of a fuel pump, and not by the injection air. However, since it is desirable to vary the quantity of fuel it is also desirable to vary the quantity of air whereby the fuel is injected into the cylinder. It is particularly advantageous to prevent the admission of too much injection air, for the excess air expanding in the cylinder may result in cooling, which would 65 prevent ignition, or at least impair the efficiency of the fuel.

One of the objects of this invention is to provide a simple means for adjusting or controlling the mechanism for actuating the inlet valve, or injection valve, so as to vary the movements of said valve. By properly varying the strokes of this valve, the admission of injection air can be controlled to avoid dissipation, or waste, of compressed 70 air, at the same time avoiding to a great extent the undue cooling which has heretofore resulted from the admission of excess injection air. In the preferred form of the invention, this is accomplished by an adjustable member adapted to change the leverage of a lever arm in the valve operating mechanism, thereby varying the movements of the inlet valve, and this adjustable member may be under the control of a speed 75 governor, but it is to be understood that the invention is not limited to this precise combination of elements.

In the manufacture of engines of the type herein referred to, the valve mechanism is carefully designed to open and close the injection valve at predetermined periods in the cycle of operations, and after these opening and closing periods have been properly determined, they should remain fixed and unchanged during the subsequent operations of the engine. I therefore prefer to vary the movements of the valve without varying the predetermined periods in which the valve is opened and closed. This may be accomplished, as will be hereinafter described, by using a cam which operates a valve actuating lever during a certain fixed period in the cycle of operations, and by changing the leverage of said lever to vary 80 85 90 95 100 105 110

the movements of the valve without changing the time of operation of the lever.

Fig. I is a fragmentary view illustrating a portion of an internal combustion engine embodying the features of this invention.

Fig. II is an enlarged vertical section illustrating the injection valve, or inlet valve, and the adjustable valve operating means.

- 10 10 A designates an engine cylinder provided at its upper end with a hollow head B, said head having a top wall 1 and a bottom wall 2 separated therefrom to provide a space for the cooling water.
- 15 15 The injection valve, or fuel inlet valve, comprises a valve member 3 in the form of a long rod or needle adapted to open and close an inlet port 4, through which the fuel is discharged into the cylinder. The valve member 3 is slidably mounted in a guide tube 5 suitably secured in a valve housing 6. A sleeve 7, surrounding the valve housing 6, extends from the top wall 1 of the cylinder head to the bottom wall 2, said sleeve being secured by means of a threaded ring 8 screwed into the top wall. This sleeve is intended to prevent the water in the hollow cylinder head from coming into contact with the valve housing 6.
- 20 20 30 30 9 designates an air conducting pipe through which the injection air under a high pressure is conducted to a passageway 10 leading into the upper portion of the valve housing. 11 designates an oil conducting pipe through which the oil is forced into a long angular passageway 12, leading from a point above the cylinder head to the lower portion of the valve housing. The oil is thus admitted into the annular space between the
- 25 25 35 35 40 40 45 45 50 50 55 55 60 60 65 65 70 70 75 75 80 80 85 85 90 90 95 95 100 100 105 105 110 110 115 115 120 120 125 125 130 130 135 135 140 140 145 145 150 150 155 155 160 160 165 165 170 170 175 175 180 180 185 185 190 190 195 195 200 200 205 205 210 210 215 215 220 220 225 225 230 230 235 235 240 240 245 245 250 250 255 255 260 260 265 265 270 270 275 275 280 280 285 285 290 290 295 295 300 300 305 305 310 310 315 315 320 320 325 325 330 330 335 335 340 340 345 345 350 350 355 355 360 360 365 365 370 370 375 375 380 380 385 385 390 390 395 395 400 400 405 405 410 410 415 415 420 420 425 425 430 430 435 435 440 440 445 445 450 450 455 455 460 460 465 465 470 470 475 475 480 480 485 485 490 490 495 495 500 500 505 505 510 510 515 515 520 520 525 525 530 530 535 535 540 540 545 545 550 550 555 555 560 560 565 565 570 570 575 575 580 580 585 585 590 590 595 595 600 600 605 605 610 610 615 615 620 620 625 625 630 630 635 635 640 640 645 645 650 650 655 655 660 660 665 665 670 670 675 675 680 680 685 685 690 690 695 695 700 700 705 705 710 710 715 715 720 720 725 725 730 730 735 735 740 740 745 745 750 750 755 755 760 760 765 765 770 770 775 775 780 780 785 785 790 790 795 795 800 800 805 805 810 810 815 815 820 820 825 825 830 830 835 835 840 840 845 845 850 850 855 855 860 860

vided at its upper end with an abutment collar 24 which engages the lower end of an abutment sleeve 25, the upper end of said sleeve being engaged with the tubular spring seat member 17. A light spring 26, connected to the lever 21, tends to retain the abutment collar 24 in engagement with the abutment sleeve 25. It will now be understood that the lever 21, fulcrumed at 22, may be actuated to lift the valve 3 from its seat at the lower end of the valve housing.

27 designates the usual cam shaft adapted to be driven by the engine, and 28 is a cam fixed to said shaft and adapted to engage a roller 29 at one end of a large lever 30, said cam having a projection 28 whereby movement is transmitted to said lever. This lever 30 is fulcrumed on a rod 31, and one of its arms has a flat face 32 which overlies a corresponding flat face 33 on one of the arms of the shorter lever 21. A power transmission block or rod 34 is mounted between the flat faces 32 and 33 to provide for the transmission of movement from the driving lever 30 to the driven lever 21, whereby the valve is actuated.

It is important to observe that the transmission block 34 may be adjusted along the flat faces 32 and 33, so as to occupy different positions relative to the fulcrums of the levers, and that such adjustment will result in a change of the leverage. The large oscillatory driving lever 30, actuated by the rotary cam 28, moves a fixed distance in response to each revolution of the cam, but the movement of the driven lever 21 may be varied by adjusting the transmission block 34. The degree of movement imparted to the valve will therefore depend upon the position of the adjustable transmission block. The valve always returns to the fixed closed position shown in Fig. II, for an adjustment of the transmission block 34 does not change the closed position of the valve. To reduce the lifting movement of the valve, the transmission block 34 is adjusted toward the fulcrum 31 of lever 30, and to increase the valve movement the block is adjusted away from said fulcrum.

The object in varying the movements of the valve is to prevent excess air from escaping between the valve and its seat when the valve is lifted to its open position, and it will be apparent that the volume of air escaping past the valve will be relatively small if the valve is lifted only a slight distance. The adjustable transmission block 34 serves as a means for regulating the valve movements, and it can be adjusted to economize in the use of compressed air, and to avoid undue cooling which would result from the admission of too much of the injection air.

I have previously stated that it is desirable to vary the movements of the inlet valve without changing the time in which the

valve is opened and closed. The cam 28 is properly timed to open and close the valve at fixed predetermined periods in the cycle of operations, and it is important to observe that an adjustment of the transmission block 34 will vary the vertical movements of the valve without changing the fixed periods in which the valve begins and ends its movements. A change in the leverage merely changes the degree of movement at the valve, and does not change the time in which the valve is to begin or complete its movements. A leaf spring 35, bearing against a screw on the lever 30, serves to retain the roller 29 in

constant engagement with the cam 28, thereby avoiding hammer blows when the cam projection strikes the roller 29. This spring 35 also cooperates with the spring 26 to avoid pressure on the block 34 when the cam 28 is ineffective. There is preferably a very slight space between the block 34 and the lever 30 when the cam is ineffective, so the block can be easily adjusted between the levers.

To illustrate a suitable means for adjusting the transmission block 34, I have shown an operating shaft 36 provided with a depending arm 37, and links 38 connecting said arm to the adjustable block 34. An operating arm 39, secured to the shaft 36, may be oscillated in any suitable manner to adjust the block 34 relative to the fulcrums of the levers 21 and 30. The operating arm 39 is preferably adjusted automatically by a speed governor driven by the engine.

40 designates a rotary governing shaft (Fig. I) adapted to be driven by the engine, and 41 is the governor provided with the usual collar 42 movable longitudinally of the shaft 40. The means for transmitting movement from the governor collar 42 to the operating arm 39 comprises a lever 43 actuated by the governor collar, a vertical rod 44 loosely mounted in one end of lever 43, an arm 45 to which the upper end of rod 44 is pivoted, and an arm 46 secured to the arm 45, said arms 45 and 46 being pivotally mounted on a rod 47. A spring 48, surrounding the vertical rod 44, lies between the lever 43 and a collar 49 on the rod 44, so as to yieldingly transmit upward movement from the lever 43 to the rod 44. Downward movement is firmly transmitted from the lever 43 and through a nut 44' on the lower end of rod 44. A sleeve 50, at the upper portion of Fig. II, is pivoted at 51 to the operating arm 39. A long connecting rod 52, pivoted to the arm 46, is provided at its upper end with a reduced extension 52' slidably mounted in the sleeve 50, said rod having a shoulder 53 which normally engages the lower end of sleeve 50. A spring 54, surrounding the reduced extension 52', yieldingly holds the shoulder 53 in engagement with sleeve 50.

Through the medium of the elements just

described, including the springs 48 and 54, the governor actuated lever 43 is yieldingly connected to the operating arm 39 whereby the transmission block 34 is adjusted. The block 34 will, therefore, be adjusted automatically in response to changes in the speed of the engine governor; and if the governor actuated lever 43 should be operated while the block 34 is clamped between the faces 32-33, one of the springs 48 or 54 will yield to prevent breakage or other injury to the connecting elements. Thereafter, when the transmission block 34 is released, the spring 48 or 54 will act upon the connecting elements to adjust said block 34.

I claim:

1. An internal combustion engine of the high compression type having a fuel inlet valve, means for conducting fuel and compressed air to said inlet valve so as to inject the fuel into the engine, valve operating means whereby said inlet valve is opened and closed at fixed periods in the cycle of operations, said valve operating means comprising an operating cam, a driving lever actuated by said cam, a driven lever whereby said valve is actuated and a power transmission member slidably mounted between said levers and being independent therefrom, said power transmission member being movable to different positions relative to the fulcrums of said levers so as to vary the movements of said valve, a speed governor, and yielding means connected to said speed governor and to said power transmission member whereby said power transmission member is automatically adjusted to vary the movements of said valve.

2. An internal combustion engine having an inlet valve, means for conducting liquid fuel and compressed air to said inlet valve so as to inject the fuel into the engine, valve operating means whereby said valve is opened and closed to control the admission of the compressed air and fuel, said valve operating means including a lever connected directly to said inlet valve and a transmission member cooperable with different parts of said lever to transmit movement to said valve, said transmission member being movable relative to the fulcrum of said lever to engage different points on said lever, a speed governor, and yielding means connected to said speed governor and to said transmission member whereby said transmission member is automatically adjusted to regulate the admission of said compressed air.

3. An internal combustion engine having an inlet valve, means for conducting liquid fuel and compressed air to said inlet valve so as to inject the fuel into the engine, valve operating means whereby said valve is opened and closed to control the admission of the compressed air and fuel, said valve operating means including a power trans-

mission member independent of said valve operating means and adjustable to vary the degree of movement of said inlet valve, a speed governor, and yielding means connected to said governor and to said power transmission member whereby movement is transmitted from said speed governor to said power transmission member.

4. An internal combustion engine having 10 an inlet valve, means for conducting liquid fuel and compressed air to said inlet valve so as to inject the fuel into the engine, valve operating means whereby said valve is opened and closed to control the admission 15 of the compressed air and fuel, said valve operating means including a power trans-

mission member adjustable to vary the degree of movement of the inlet valve, said power transmission member being firmly held to prevent adjustment thereof during 20 the operation of said valve, a speed governor, and yielding means whereby movement is yieldingly transmitted from said speed governor to said adjustable power transmission member, said means including a coil 25 spring which permits the operation of said last mentioned means even though said power transmission member be immovably held.

In testimony that I claim the foregoing I 30 hereunto affix my signature.

REINHARD HILDEBRAND.
